UNITED STATES PATENT OFFICE.

GEORGE H. BARTLETT, OF SHORT HILLS, NEW JERSEY, AND OBED PECK,
OF ROWE, MASSACHUSETTS; SAID PECK ASSIGNOR TO SAID BARTLETT.

TOOL-HOLDING BOX.

SPECIFICATION forming part of Letters Patent No. 388,334, dated August 21, 1883.

Application filed February 9, 1883. Serial No. 263,524. (No model.)

To all whom it may concern:

Be it known that we, GEORGE H. BARTLETT, of Short Hills, in the county of Essex and State of New Jersey, and OBED PECK, of Rowe, 5 Franklin county, Massachusetts, have invented certain new and useful Improvements in Tool-Holding Boxes; and we do hereby declare that the following is a full, clear, and exact description thereof, reference being had to the accompanying drawings, and to the letters of reference marked thereon, which form a part of this specification.

This invention relates to an improved box, tool-holder, or receptacle for auger-bits or similar tools of that kind having a series of separate compartments or cells for each of the several tools placed therein. A box embodying our invention is made of wood or similar substance, and is provided with a series of 20 elongated cells arranged side by side and parallel with each other, with their open ends at one side or face of the block. Said block consists of three or more pieces or slabs of wood or other material, the exterior pieces or slabs 25 having recesses formed in their inner faces, and the intermediate pieces or slabs having recesses formed in both faces, which recesses, when the pieces are fastened together, form the several compartments of the tool holder or receptacle. The lower ends of the recesses are closed by a bottom piece secured to the lower surface or end of the block, and the recessed cover is hinged to the top of the block for holding the tools in place within the 35 recesses.

The invention may be more readily understood by reference to the accompanying drawings, in which—

Figure 1 is a perspective view of a tool holder 40 or receptacle constructed in accordance with our invention. Fig. 2 is a transverse section thereof. Fig. 3 is a transverse horizontal plan through the slabs or layers forming the body of the box shown in Fig. 1, the slabs being separated from each other. Fig. 4 is a horizontal plan showing a box or receptacle consisting of four slabs or pieces.

As shown in Figs. 1, 2, and 3, A is the main part or body of the receptacle, and B the cover 45 thereof. The main part or body comprises a block, A, which is formed by three separate

layers or slabs, A' A² A³, secured together side by side by means of glue or otherwise. The slabs A' A³, forming the front and rear surfaces of the block, are provided at their inner faces 55 with recesses a' a' a' a³ a³. The intermediate slab, A², is provided upon one side with recesses a² a² a² and upon its opposite side with recesses a⁴ a⁴ a⁴. The recesses a' a' a² a² a² form one set or row of cells or compartments a a a, 60 while the recesses a³ a³ a³ and a⁴ a⁴ a⁴ form another set or row of cells or compartments a a a, when the said several layers A' A² A³ are secured together. The bottoms of the said several compartments a a a are, as shown in said 65 Figs. 1 and 2, closed by means of a bottom piece, A⁴, nailed, glued, or otherwise secured to the lower surface of the block A.

The cover B is shown as hinged at one side by hinges b to the block, and is provided at its 70 opposite side with a catch, b', by which it may be held closed.

In constructing a box or tool-holder such as is shown in Figs. 1, 2, and 3 the slabs or layers A' A² A³ will preferably be constructed by 75 first grooving longitudinally a long strip or board with grooves of the proper size and shape to form the recesses a' a² a³ a⁴, and by then cutting the said board or strip into lengths suitable to form the said slabs or layers and thereafter securing the same together in the manner above described.

The hinged cover or lid B' is provided with a series of holes or recesses, b² b², in its under surface corresponding in position with 85 the several cells or compartments a a of the block. The said cells a a are made of slightly less depth than the length of the bits or tools, so that the shanks of said tools will extend above the top of the block and will enter 90 the recesses b² b² when the cover B' is closed. The ends of the shanks will thus project above the blocks when the cover is open, and may be easily grasped for removing the tools separately from the cells. A cover such as is 95 shown in Fig. 1 may obviously have a single large and shallow recess in its under face in place of the several recesses shown.

A tool-holding block made, generally, in the manner set forth may be provided with two or 100 more internal layers, instead of with a single intermediate layer, such as is shown in Figs.

1, 2, and 3. A construction of the kind last referred to is illustrated in Fig. 4, wherein a block, C, is shown provided with a series of cells, $c c c$, arranged in three separate rows, 5 said block being formed by means of two exterior layers, C' and C^3 , together with two intermediate layers, C^2 and C^3 .

The cells or compartments for the bits or tools may be of any cross-sectional shape necessary or desirable for the particular purpose for which the holder is to be used. As shown in Figs. 1 to 3, the said cells are made circular in shape. In the construction shown in Fig. 4, however, they are square.

15 It has been proposed heretofore to make a tool-receptacle of the general character herein shown by boring a series of holes side by side in a block of wood to form cells to receive the tools. A construction of this kind is not 20 adapted for general application, for the reason that the boring of a series of holes side by side is a slow and expensive operation, inasmuch as the holes must be bored one by one, and is a troublesome one by reason of the fact 25 that the holes can seldom be bored straight and parallel with each other, owing to the deflection of the boring-tool by the grain of the wood.

By making the block of three or more 30 grooved layers or slabs, as herein shown and

above described, we avoid the difficulties above mentioned, and are enabled to construct the block in a simple, cheap, and expeditious manner.

We claim as our invention—

As a novel article, a tool holder or receptacle consisting of two exterior slabs or layers grooved upon their inner faces and one or more intermediate layers grooved upon both faces, said layers being secured together with 40 the grooves therein opposite each other to form a series of compartments or cells, a bottom secured to the lower end of the slabs or layers, and a cover connected with the upper or opposite ends thereof, said cover being recessed in its inner face to receive the ends of tools which project from the recesses, substantially as described.

In testimony that we claim the foregoing as our invention we affix our signatures in presence of two witnesses.

GEORGE H. BARTLETT.
OBED PECK.
